UNITED STATES PATENT OFFICE.

WILLIAM STRAIT, OF ELMIRA, NEW YORK.

SIDE-HILL PLOW.

SPECIFICATION forming part of Letters Patent No. 540,846, dated June 11, 1895.

Application filed November 14, 1894. Serial No. 528,768. (No model.)

To all whom it may concern:

Be it known that I, WILLIAM STRAIT, a citizen of the United States, residing at Elmira, in the county of Chemung and State of New York, have invented certain new and useful Improvements in Side-Hill Plows, (Case B;) and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to plows.

The object of my invention is to provide a sidehill plow and its reversible moldboard with novel means for shifting the colter and jointer.

20 Figure 1 represents a side elevation, partly broken away, of a plow embodying my invention. Fig. 2 is a sectional view on the line $\alpha\alpha$ of Fig. 1. Fig. 3 is a sectional view on the line $\gamma\gamma$ of Fig. 1. Fig. 4 is a detail view of the front edge of the standard. Fig. 5 is a detail side elevation of the standard and handles, showing the colter removed from its position in Fig. 1 and a jointer substituted therefor. Fig. 6 is a perspective view of the 25 jointer and its operating mechanism.

30 The standard A is provided with an inclined fore and aft hole or opening B within which either the colter C or the jointer D may operatively rest. When the colter C is used with this sidehill plow, the relation of the parts is as shown in Figs. 1, 2 and 3.

35 The opening B in the front of the standard is vertically elongated, and the shank E of the colter is of similar dimensions as said opening at that point. The opening B flares laterally from the front toward the rear edge of the standard so as to provide a lateral oscillating motion to the colter-shank.

40 F are the shifting handles of the plow pivoted at any suitable point, and carrying a plate G bolted on the under side thereof, and provided with lugs H which act, through the intervention of the lever I to oscillate and shift the colter C whenever the handles and the moldboard are shifted.

45 The lever I oscillates upon a pivot J car-

ried in the standard and its upper end is recessed providing an opening K through which the rear end of the colter shank E projects. A curved bolt M is secured to the lever I and traverses this opening K passing through an eye in the rear end of the shank E. The lower end of lever I constitutes a projection which lies between the lugs H on the handles.

55 The opening K is of such lateral dimensions that the lever I oscillates to some extent before that actuating side wall of the opening (depending in what direction the colter or jointer is to be shifted) comes in contact with the shank of the same for shifting it. The 60 initial part of this motion in either direction is lost motion, the end movement of the oscillation accomplishing the shifting of the shank of the colter or jointer, such shank projecting through said opening.

65 In operation, when the moldboard and handles are shifted by being thrown to the right, for example, the lugs H are thrown to the left, moving the lower end of lever I in that direction, and the upper end thereof in the 70 opposite direction, or to the right. The opening K, also moving to the right, its rear edge comes in contact with the colter shank E shifting it laterally to the right until it bears against the side wall of the opening B where 75 it is securely held. The colter C, being at the opposite end of the shaft is carried to the left for its operative position when the moldboard is thrown to the right, the colter and share being in alignment. It will be seen 80 that a precisely reverse operation takes place when the moldboard and handles are shifted to the left. The bolt M passing through the 85 opening B holds the colter in operative position and at the same time allows a free 90 operative movement to the shank.

O is a lug formed on the rear of the standard which overlaps the upper edge of the lever I and aids in holding that lever in place during its movements.

95 When it is desired to substitute the jointer D for the colter C the latter is removed and the rotary shank P of the jointer inserted in the opening B, said opening having circular portions R therein within which the shank P has its bearings. The lever I is then removed, and the lever collar S is substituted

and secured to the rear end of the shaft P, the collar S being received within the lug O on the standard. The casting T is then bolted on the upper end of the handles, and has a 5 pin which engages with the collar lever S for shifting the jointer when the moldboard and handles are shifted.

I claim—

1. A colter or jointer shifting lever provided with an intermediate pivot having a projecting arm on its lower end and an opening in its upper end, within which the colter or jointer is shifted.

2. A colter or jointer shifting lever having a projecting arm on its lower end, an opening 15 in its upper end provided with a bolt for hold-

ing the shank in place, and a pivot located between said ends.

3. In a sidehill plow the combination of a colter fulcrumed to the front edge of the 20 standard and oscillating laterally, a lever pivoted to the rear of the standard having an opening or slot above its pivot through which the colter projects, and handles for shifting the lever and colter.

In testimony whereof I affix my signature 25 in presence of two witnesses.

WM. STRAIT.
